KNITTING MACHINE

Harry McAdams, Reading, Pa., assignor to The
Nolde and Horst Company, Reading, Pa., a cor-
poration

Original application June 20, 1936, Serial No.
86,420. Divided and this application Novem-
ber 11, 1937, Serial No. 174,099

1 Claim. (Cl. 66—133)

This invention relates to improvements in
knitting machines.

The present application is a division out of
my co-pending application Serial No. 86,420,
5 filed June 20, 1936.

The primary object of the invention is the
provision of a knitting machine with improved
means for manipulation of yarns in a machine
adapted to knit seamless stockings in string-
10 work.

A further object of the invention is the pro-
vision of an improved knitting machine adapted
to knit seamless stockings in stringwork having
improved means for the feeding of and guiding
15 and manipulation of a splice yarn; the machine
being of the dial and cylinder rib knitting type.

A further object of the invention is the pro-
vision of improved binding and cutting means
20 for the yarns of a cylinder and dial type of rib
knitting machine.

A further object of this invention is the provi-
sion of a sinker ring construction in a knitting
machine having improved yarn guiding and con-
trolling and sinker controlling means associated
25 in a cooperative relation therewith.

Other objects and advantages of this invention
will be apparent during the course of the
following detailed description.

In the accompanying drawings, forming a part
30 of this specification, and wherein similar refer-
ence characters designate corresponding parts
throughout the several views,

Figure 1 is a side elevation of the improved
knitting machine.

Figure 2 is a plan view of the improved knitt-
ing machine with a portion of the head of the
knitting machine proper removed.

Figure 3 is an enlarged fragmentary vertical
40 sectional view taken through the dial and cylin-
der construction of the knitting machine, showing
associated details.

Figure 4 is a developed view showing the cylin-
45 der needle, jack, and dial needle control finger
lay-out of the knitting machine, and associated
cam and other yarn controlling parts as they
will appear during the knitting of plain knitted
work upon the improved rib machine.

Figure 5 is a top plan view of my improved
50 sinker cam cap, showing associated therewith
an improved splice yarn control member which
is used during rotary knitting to guide the splice
yarn out of the way of the dial and dial needles.

Figure 6 is a bottom plan view of the sinker
55 cam cap.

Figure 7 is a bottom plan view of the dial cap,
showing the cam arrangement.

Figure 8 is a fragmentary perspective view
showing a binder and cutter which may be mounted
upon the dial of the knitting machine. 5

Figures 9, 10 and 11 show the associated stitch
transfer relation of dial and cylinder needles in
the act of transferring a stitch loop from a dial
needle to a cylinder needle.

In the drawings, wherein for the purpose of 10
illustration are shown preferred and modified
embodiments of the improved knitting machine
and the details thereof, the letter A may generally
designate the improved knitting machine. It includes
15 a frame B having a rotary cylinder C and a dial D.
Drive means E is provided for driving the cylinder C and bed of the dial D, and
for operating a pattern control drum arrangement F and a pattern chain G. A set H of dial
needles is provided and also a set K of cylinder 20
needles. Selective means L is provided for operating
the dial needles for various purposes.

The frame B of the machine includes a cabinet
portion 25 within which the drive mechanism
of the machine is mounted. The frame is sup-
ported upon suitable legs 26 or in other manner
and it has a top table 27 which supports the
cylinder for vertical movement. 25

The cylinder C is longitudinally slotted on
the outer surface thereof for reciprocably receiv-
ing needles and jacks therein; the needles being
mounted in the upper part of the cylinder and
the jacks in the slots below the needles in the
usual manner. An anti-friction bearing con-
struction 30, shown in Figure 3 of the drawings,
35 has a race 31 directly supporting the lower end
of the cylinder C. The cylinder and dial are
driven as described in my parent application
Serial No. 86,420, filed June 20, 1936.

The top construction of the cylinder is rather 40
conventional. It includes a top ring 50, for slid-
ably supporting the sinkers 51. The sinker con-
trol arrangement further includes the sinker or
web holding bed 52 which is keyed at 53 to the
cylinder. The sinker cam ring 54 is mounted 45
on the bed and of course is provided with move-
ment limiting lugs 290 thereon, best shown in
Figures 5 and 6 of the drawings, located at op-
posite sides of the usual stop post 291. The
sinkers 51 are of general construction and need 50
not be further described, since their nature, func-
tion and construction is well understood in the
art to which this invention relates. Reference
in this connection may be made to U. S. Patent
#1,467,691. The sinker cam ring 54 has an an- 55

nular channel in the undersurface thereof, in which the butts of the sinkers ride. In this channel the sinker cam ring 54 is provided with a sinker withdrawing cam 60 and sinker advancing cams 61 and 62. The advancing cams 61 and 62 are pivoted at their proximate ends at 63 and are adapted to be retracted at different operations throughout the knitting of the stocking. Means is provided to move the advancing cams 61 and 62 comprising a circumferentially movable ring 65 socketed in an annular channel in the top of the cam ring 54, as is shown in Figures 3 and 5 of the drawings. This ring 65 is provided with cams 65a, slotted to receive pins 67 of the cams 61 and 62 and having throw portions 65b to move the cams 61 and 62 to a retracted position. Cams 61 and 62 are advanced and retracted as the ring 65 is reciprocably moved in its channel on the sinker cam ring 54. A spring 64 normally maintains the cams 61 and 62 in sinker advancing position.

Referring now to the pattern control drum arrangement F, with reference to Figures 1 and 2 of the drawings it will be seen that this drum arrangement is compactly located at the rear of the machine in an easily accessible and convenient location. It essentially consists of a shaft 75 rotatably supported and connected by brackets 76 to the frame of the machine; one of the brackets 76 being located intermediate the ends of the shaft 75 to give it central support. The drum arrangement includes the drum F' and the drum F'' and on these drums a circumferential series of lugs are provided for operating the various levers and parts of the machine. A compact and accessible arrangement of levers includes a shaft 77 which is pivotally supported by the brackets 76 of the machine; said shaft extending parallel with the drum and at a location between the drums and the cylinder, and on a level approximately in a line tangent to the top of the drums. On this shaft 77 are located bell crank levers which are pivoted for oscillative action thereon; the said bell crank levers having arm portions which operate at their ends on lugs on the drum, the opposite ends of said levers extending substantially vertical and having rod attachments with the different features of the machine to be operated. With reference to the sinker cam control ring 65 immediately above described, one of the levers 79 of the shaft 77 has the upper end of its vertical arm supporting a connecting rod 80; the opposite end of said connecting rod 80 being attached in a suitable opening 82 provided in the ring 65 (see Figures 2 and 5). Rocking of the lever 79 incident to operation off the drum F'' will cause movement of the ring 65 and throw the cams 61 and 62 into retracted position.

60 The pattern drums are controlled and driven as described in my above identified parent application.

Referring to the dial construction D and the selective means L for operating the dial needles thereof, a very compact bracket or yoke construction is provided for supporting the dial mechanism over the cylinder in such manner that all of the parts of the same are readily accessible and so that the dial may be moved to an out of the way position with respect to the cylinder. This bracket or supporting yoke construction for the dial is generally of inverted U-shape formation. It includes a stationary bracket 100, at the left side of the machine, bolted at 75 101 to the machine bed 27 and extending upward

diagonally towards the cylinder to a point about even with the top of the cylinder, where it pivotally supports at 102 a dial supporting arm 104. This arm includes a portion 105 which really forms an extension of the bracket arm 100 and is inclined diagonally towards the cylinder when the dial is placed over the cylinder. It further includes the horizontal supporting portion 106 which lies horizontally over the cylinder, as shown in Figure 1. The yoke construction for supporting the dial further includes the bracket arm 107 mounted on the bed of the machine at the opposite side from the bracket 100, as shown in Figure 3 of the drawings, and which extends diagonally upward, inclined towards the cylinder and at its upper end is adapted to receive the free end of the dial supporting arm 104 in resting relation thereon; an adjusting screw 108 being provided on the end of the arm 104, for abutment with the upper end of the arm 107, to regulate the spacing of the dial above the cylinder when in knitting position.

The dial is supported from the yoke by a depending pin construction as specifically described in my above identified parent application. 25

The dial construction includes the bed 118 and the stationary dial cap 129. This dial cap is in the form of a ring so that the lower ends of the dial needle actuating fingers 130 (comprising part of the selective means L for operating the dial needles) may engage the said dial needles either at the rear ends thereof or on special butt arrangements which may be provided on the dial needles in order to move them for accomplishing various operations. 35

Referring now to the dial bed construction 118, as is shown in Figure 3 of the drawings, the same is provided with slots 131 which reciprocably receive the needles 132 of the set H of dial needles.

The dial needles 132 are of the nature and construction set forth in my co-pending application Ser. No. 68,526, filed March 12, 1936, now Patent No. 2,111,476. They each include a body portion 135 having a shoulder 136 intermediate its ends behind the points where the latch closes. 45 The needle has the usual hook end latch. Immediately rearwardly of the shoulder the body 135 is laterally recessed upwardly from the lower edge thereof. Facing this recess is a spring arm 138 which at its fore end is free of direct attachment 50 to the needle and is provided with a lip 139 adapted to fit in the recessed portion 140 in the lower edge of the needle. The arm 138 is spring bowed as shown in Figures 9 and 11 of the drawings and faces the concaved recess 137 in the body of 55 the needle to provide an eye which is vertically disposed when the dial needle is positioned in the dial bed. The head of the cylinder needle may readily slip into this opening notwithstanding that the cylinder needle is directly opposite the line of travel of the dial needle. The lip 139 prevents the stitch catching in the eye.

The dial cap 129 is best shown in Figures 3 and 7 of the drawings. It has a central opening 142 to receive the lower ends of the dial actuating fingers 130. The dial needles are initially projected by the fingers 130 both for transferring stitches from dial needles to cylinder needles and at a second location to receive yarns when they are used in connection with the cylinder 70 needles for knitting rib work. The dial cap 129 is provided with the dial needle butt receiving groove 144 which receives the dial needles when they are inactively positioned. The dial needles are projected into stitch transfer position by a 75

cam 145, comprising part of the dial cap, when the butts of the needles 12 are thrown into the groove 146 surrounding this cam. Normally, the butts of the dial needles travel inactively in the 5 groove 144. The dial needles are projected so that their butts will engage the cam 145 by the dial needle selector fingers 130. The opening 142 in the cap is widened at 147 to enable the lower ends of the fingers 130 to push the dial 10 needles so their butts will engage against the cam 145. In the dial cap a second cam 150 is used to project the dial needles into yarn receiving relation for knitting rib work. The central opening 142 of the dial is cut away at 151 so as 15 to enable the fingers 130 to project the butts of the dial needles into engagement with the cam 150.

The dial needles are projected by pivoted fingers 130. At their upper ends the fingers 130 20 may be provided with any desired arrangement of butts thereon. In the example shown in the drawings substantially one half of the members 130 are provided with butts 130^a at an upper level and the remainder of the said dial needle 25 control members 130 have butts 130^b at a lower level. The upper level butts 130^a are arranged, as shown in Figure 4, over substantially one half of the short butt cylinder needle section and substantially one half of the long butt cylinder 30 needle section.

The set K of cylinder needles includes long butt needles 230 and short butt needles 231. Below alternate long butt needles 230 there are provided jacks 232 having long butts at a lower 35 level, and below alternate short butt needles there are provided jacks 233 having short butts at a lower level. Long butt jacks 234 have long butts at an upper level. They are positioned in an alternating relation with the cylinder 40 needles, and similarly jacks 235 having short butts at the upper level (complementary to the jacks 234) are provided in alternating relation below the cylinder needles. These short butt upper level jacks 235 are spaced across the division 45 line of the long and short butt needles, that is, half of them are in the long butt needle section and half of them in the short butt needle section, and that is also true for the upper level long butt jacks 234, for a purpose which will 50 be subsequently described. It should be noted in this connection that the upper level short butt jacks 235 are located below cylinder needles which are inactive during rib knitting and which receive stitches from the dial needles actuated 55 by those dial needle actuating fingers 130 having the butts 130^b thereof at the lower level.

The frame bed 27 of the machine has a cam supporting ring or table 240, which is spaced above the bed 27 so that access may be had to 60 cams or operating features which may be placed between the table 240 and the bed 27, shown in Figure 1. The table 240 supports main stitch cam block 244, shown in Figures 1 and 3 of the drawings; the widening pick attachment 430 65 shown in Figure 2 of the drawings, and other cam and cam operating levers to be subsequently described.

The machine is preferably provided with yarn feeds in the nature of the usual levers pivoted 70 at 245 on the latch ring 246. This latch ring is bolted at 247 upon the swinging arm 105 of the dial supporting structure 104 (see Figure 3) and the dial cap 129 is in turn bolted at 250^a to the latch ring to hold it against rotation.

75 The five yarn feed fingers are used for feeding

plating, splice, top, binding, and lining yarns to the needles. The finger 252 which feeds yarn for the knitting of the rib top also is used to knit the heel and toe of the stocking. By reference to Figures 1 and 2 of the drawings it will be seen 5 that these fingers 250 to 254 inclusive are swung into action by means of reciprocating push rods 256 (see Figure 1) supported by brackets 257 on the machine. These push rods 256 in turn are actuated by suitable levers 258, 259, 260, 261 and 10 262, for the fingers 250, 251, 252, 253 and 254 respectively. The levers 258 to 262 inclusive are pivoted on the shaft 77 and at their outer ends are raised by lugs on the drum F' for throwing the push rods 256 into engagement with the 15 respective yarn fingers.

At the location of transfer of the stitches from dial needles to cylinder needles a brush 264 is located for throwing the latches of the needles 20 open.

It was before mentioned that the sinker cams 61 and 62 are opened and closed at different operations throughout the stocking. Inasmuch as the sinker cap oscillates during reciprocation of the machine, as limited by the lugs 290 thereon engaging against the post 291 (see Figure 2), it will be desirable to hold the sinker ring 54 against movement when it is desired to advance the cam ring 65 for throwing the sinker cams 61 and 62 to an inoperative position. To that end 25 a lever 293 is pivoted at 294 upon the machine, as shown in Figure 2, which is adapted to engage against an offset 295 on the sinker cam ring 54. The lever 293 is actuated off of the lever 295 and the latter is pivoted upon the shaft 77 and 30 actuated off of drum F'. It is connected by means of a rod 296 with the lever 294 above described.

The frame of the machine is provided with a bobbin supporting table 300 rearwardly of the 40 lever arrangement which operates off the lugs of the drums F' and F''. On this table are supported bobbins 301 for feeding the various yarns to the feed fingers 250 to 254 inclusive. Figure 1 shows the arrangement of yarns. Plating 45 yarn is indicated at 302, the splice yarn is indicated at 303, the heel, toe and rib top yarn is indicated at 304, the binding or selvage yarn is indicated at 305 and the lining yarn is indicated at 306. All of these yarns except the yarn 304 50 are fed through appropriate tensioners 307 and then extend to their respective feed fingers 250 to 254 inclusive.

The rib top yarn 304, which is also used in knitting the heel and toe has the normal tensioner 308 operating thereon, and it is provided with means which places additional tension on the yarn when knitting the heel and toe. This means includes a conventional tensioner 310 having upper and lower plates between which the 60 yarn passes. The lower plate is movably supported by an arm 315, shown in Figure 2 of the drawings, which is pivoted at 316 and normally spring urged at 317 into tensioning position. A connecting rod 319 is attached to the arm 315 65 and moves upwardly and downwardly to throw the tensioner into and out of action. The rod 319 is pivoted at its lower end to a lever 320 which in turn is pivoted at 321 upon a bracket of 70 the frame of the machine, as shown in Figures 1 and 2 of the drawings. This lever 320 is connected by a rod 323 to one of the drum actuated levers 324. The drum actuating lever 324 is pivoted on the shaft 77 and lug actuated off the 75

drum F' in order to throw the yarn tensioner 310 into or out of yarn tensioning position. Means is provided to hold the splice yarn in an out of the way relation with respect to the dial during knitting of the high splice heel and double sole during rotary knitting, since otherwise the splice yarn would become entangled with the dial and the dial needles. This splice yarn guard consists of a finger 340, shown in Figure 5 of the drawings, which has a curved end facing the splice yarn feed finger. This guard 340 moves into and out of position across the cylinder needle line, as shown in Figure 5. In the full line position shown in Figure 5 it is out of action, and in its dotted position it is across the cylinder needle line and in position to engage the splice yarn and guide and maintain it below the dial in an out of the way relation until the splice yarn is taken by the needles which are intended to take it during the next rotational movement. This guard finger 340 enters across the needle line at the knitting wave opening in the cylinder needle set directly above the low point in the stitch cast-off cam, as shown in Figure 4 of the drawings.

The splice yarn control finger 340 is mounted upon a movable supporting plate 341, slotted at 342. A screw or pin 343 on the cam ring 54 supports the splice yarn guide member for reciprocating movement into its operative and inoperative positions. A pin 344 assists in guiding the movement of the splice yarn guide. A spring 345 normally urges an edge of the guide 341 against the pin 344, and a spring 346 normally throws the yarn guide to an inoperative position as indicated in the full line view of Figure 5 of the drawings. Referring to Figure 2 of the drawings in conjunction with Figures 5 and 6 it will be noted that a lever 350 is pivoted on the same pivot 294 as the lever 293; said lever 350 having a bifurcated end which engages a pin 351 on the splice yarn guide finger 340 for the purpose of advancing the splice yarn guide 340 into operative position as indicated in the dotted lines in Figure 5 of the drawings. This lever 350 is operated off of a lever 352 pivoted on the shaft 71, as shown in Figure 2.

An binder and cutter for cutting and holding the yarns is mounted upon the dial cap 129 of the machine. This binder and cutter is generally designated at 360 in the drawings. As shown in Figure 8 the binder and cutter includes a shaft 361 mountable by suitable brackets 362 on the dial cap 129. A binder arm 363 is spring urged downwardly by a spring 364 (spring shown broken off) for holding yarns after they are severed, and a loose pivoted binder 365 cooperates therewith. The shaft 361 is provided with a cutter bar 366 which operates in a depression 60 in the dial cap to sever the yarn. This cutter is normally spring urged into cutting position by a spring 368. An extension arm 370 on the cutter bar 366 engages the arm 363 to lift the latter when the cutter bar is moved to an open position. This extension 370 has a link 371 which is provided with an opening therein. The latch ring 246 is provided with a support 375 with which a yarn cutting operating lever 376 is pivoted as at 377; this lever 376 loosely extending 70 into the link 371 for raising and lowering the cutter bar. The means for operating the lever 376 consists of a lever 380 shown in Figures 2 and 3 of the drawings, pivoted at 381 upon a suitable bracket mounted upon the latch ring; 75 this operating lever 380 having a pin at its free

end adapted to operate on the lever 376. The lever 380 is bell cranked, and at its opposite end it has a connecting rod 384, extending for connection to one of the drum actuated levers 385 which are pivoted on the shaft 71 and actuated 5 by lugs off of the drum F'.

Cylinder needle actuating cams 410, 411, 413, and 414 are actuated off of levers 416 pivoted on the cam bed 240 of the machine. These cams 410, 411, 413 and 414 are respectively actuated 10 off of drum actuated levers 418, 419, 420 and 421 which are pivoted upon the shaft 71 and are lug actuated off of the drum F'; the said bell crank levers 418 to 421 being connected by rods 422 with the various levers 416. A pair of 15 jack actuating cams 425 and 426 are provided on the machine; the same being actuated off of levers 427 and 428 pivoted on the shaft 71 of the machine and actuated off of the drum F'; the actuation of these cams being accomplished in 20 the same manner as the cams 410 to 414 above described. These cams 425 and 426 are located in the space between the table 240 of the machine and the bed 27.

All of the rest of the jack and needle actuating cams, except those above described, are stationary.

During knitting of the rib top the sinker cams 61 and 62 are thrown out of action. Briefly this is accomplished by holding the sinker cam 30 ring 54 stationary through engagement of the lever 293, shown in Figure 2 of the drawings, with the ring, and the sinker cam retracting ring 65 is then rotated through its control off the pattern drum. The slots 65b provided on 35 this sinker retracting ring 65 operating on the pins 67 will throw the sinker cams 61 and 62 out of action, to the dotted line position shown in Figure 6.

The leg is knitted for the desired number of 40 courses, according to the size of the stocking, and the splice yarn finger 251 is thrown into action at the start of knitting the high heel splice. As this splice finger 251 is thrown into action the splice yarn guide 340 above described is thrown into 45 action to the dotted position shown in Figure 5 of the drawings in order to guide the splice yarn under the dial. This high splice section continues for about fifty courses until we reach 50 the heel pocket. Then the yarn 304 is thrown out of action and also guide 340.

Various changes in the shape, size, and arrangement of parts may be made to the form of invention herein shown and described, without departing from the spirit of the invention or 55 the scope of the claim.

I claim:

In a knitting machine a cylinder, a set of independent cylinder needles, a dial, a set of independent dial needles, means for actuating the 60 cylinder and dial needles for knitting fabric including cam means for projecting and retracting the dial and cylinder needles to cast stitches therefrom, means for feeding yarn to a portion of the cylinder needles, a yarn guide slidably 65 mounted for radial reciprocation into and out of the knitting wave of the cylinder needles for the purpose of engaging said yarn and preventing entanglement with the dial and dial needles, spring means normally urging said yarn guide 70 member to an inoperative relation, and pattern controlled means for radially urging said reciprocal yarn guide into the knitting wave.
